DRAFTING INSTRUMENT

Rolla H. Wahle, Portland, Oreg.

Application June 11, 1946, Serial No. 676,030

2 Claims. (Cl. 33—41)

1

This invention relates to a drafting instrument and more particularly to a drawing pen.

Drawing pens of the type now commonly used comprise a holder with a bifurcated member extending therefrom forming opposing pen blades which blades are adapted to be adjusted relatively so as to provide a pen capable of producing lines of various widths. However, as is well known, such pens are not capable of producing lines of a width as great as is frequently required, because of the fact that when the pen blades are spread to produce the desired width line, the ink flows too freely and a uniform line becomes impossible. Oftentimes, when producing a wide line, ink flows from the pen so rapidly that a spot is deposited and thus the drawing to that point is ordinarily spoiled beyond usage.

Another disadvantage, particularly in producing wide width lines is that such ink as is deposited within the confines of the space between the blades is not deposited uniformly; near the center of the line much more ink is deposited than at the edges. Furthermore a greater quantity of ink is always deposited than is needed. This results in a line of non-uniform character as to density of color and one which is unnecessarily slow to dry.

The prior art discloses a pen which is provided with broad marking elements so that it may be used to produce a wide line corresponding in width to that of the blades. Such a pen however is not satisfactory for use with a straight-edge because when the blades are placed adjacent the straight edge, the ink reservoir is also adjacent the straight-edge and ink flows from the reservoir to the drawing surface, thus spoiling it.

It has also been proposed to use a pen having broad blades and being provided with a guide leg whereby the ink reservoir does not contact the straight-edge, but this pen is not satisfactory for a number of reasons.

First this pen does not solve the problem of preventing ink from getting on the guide leg. Secondly, it is incapable of holding a sufficient quantity of ink for its purpose without permitting ink to flow down the guide leg. Thirdly, extreme difficulty is encountered in making line junctures with this pen because of the width of the blades adjacent the drawing surface; the pen itself presents an obstruction which prevents visual anticipation of the juncture being executed.

It is an object of this invention to overcome the foregoing disadvantages and to provide a pen of the side-flow type in which difficulties with

2

ink contamination of the guide leg are avoided, and wherein line junctures may be easily visually anticipated.

It is contemplated according to this invention 5 that a high ink capacity, accurate marking instrument be provided that is characterized by ease of operation and high visibility with respect to line junctures.

Other objects and advantages will become evident from the following detailed description and drawing wherein:

Figure 1 is a side view of the pen of this invention;

Figure 2 is a rear view of the pen of Figure 1;

Figure 3 is a sectional view on the line 3—3 of Figure 1;

Figure 4 is a bottom view of Figure 1;

Figure 5 is an inside view of a fragmentary portion of the right blade of the pen;

Figure 6 is a fragmentary front view of the marking elements;

Figure 7 is a fragmentary side view of a modified form of the pen of this invention;

Figure 8 is a rear view of Figure 7;

Figure 9 is a sectional view on the line 9—9 of Figure 7.

Referring now to Figure 1 of the drawing, numeral 10 denotes a pen holder of any suitable form and material. Extending from holder 10 is a bifurcated member comprising right and left blades 11 and 12 respectively as is shown in Figure 2. A screw 13 is provided to effect adjustment of the blades. The head of the adjusting screw may be counter-sunk in one of the blades if desired, since it is contemplated that its setting will not be altered except at times when the pen is sharpened. As is shown in Figure 2, the blades are compressed at their ends remote from the holder to form an ink reservoir.

In Figure 5, which is an inside view of a fragmentary portion of the right blade, a cutaway portion 14 and a slit 15 divide the right blade into a marking element 16 and a guide leg 17. It should be noted that guide leg 17 is beveled toward the cutaway portion 14 on its inside and outside as at 18.

Returning now to Figure 1 which affords a side view of the left side of the pen, blade 12 has its lower end cutaway to form a marking element 19 corresponding in width to the aforesaid marking element 16. Blade 12 is beveled inwardly from its outside toward the cutaway portion as shown at 20.

In use, the marking elements are adjusted 55 relative to each other in a manner hereinafter

3

described to provide an ink reservoir and a narrow ink outlet through which ink flows to the drawing surface. Movement of the pen is from left to right with the guide-leg in sliding contact with the straight-edge and drawing surface. The marking elements move in contact with the drawing surface in a line parallel to the straight-edge.

It should be noted that both blades are provided with marking elements which are of great width relative to their thickness, the reason for this being that the pen is primarily designed to produce wide lines. By varying the width of the marking elements, a pen which is capable of drawing any width line may be provided.

It was pointed out above that by cutting away a portion of blade 11 the blade is divided to form the marking element 16 and a guide leg 17. Cutting this portion away from blade 11 and the segment from blade 12 serves still another purpose in that, when properly done, the draftsman may see the drawing surface between the guide leg and marking element thereby facilitating his work.

In order to provide a pen which will afford visibility to the drawing surface so that it will be possible to actually see a line to be joined as the drawing pen approaches it, it is necessary to cut away a substantial portion from each blade. It has been found that a slit of about $\frac{3}{8}$ " in length and about $\frac{1}{8}$ " in width in the right blade and a corresponding portion from the left blade will afford sufficient view; however, a larger opening may be provided if desired. A less restricted view is afforded by the pen shown in Figure 1 because the left blade there has a segment cut from it rather than a slit. It has also been found that by beveling the surface of the left blade and guide leg toward the cutaway portion, sharper vision to the drawing surface is afforded.

Another feature of this invention which is important to note is the position of the guide leg with respect to the marking elements. The guide leg is beveled toward the inside and therefore a sharp inside edge is formed which extends substantially vertically from a point adjacent the lower end of the leg where it contacts the paper. In Figures 2 and 4 the tip of the guide leg 17 is shown as centrally positioned in the plane which passes through the central points between the marking elements. Such positioning is accomplished by forming a permanent bend or curve in the guide leg as shown in Figure 2. Thus when joining two lines perpendicularly, the inside edge of the guide leg is exactly on the line with which junction is made at the point where the marking elements meet the line and by observing the position of the guide leg it becomes easy to ascertain when the junction is perfectly executed.

The purpose of the slits 15 which extend upwardly from the cutaway portion is to provide a larger ink reservoir and at the same time prevent the ink from flowing downwardly on the guide leg. In filling the reservoir, it is not contemplated that the ink level will rise above the upper edge of the slits, for if it should, ink may flow down the guide leg and thus defeat the purpose of the slits. Furthermore, the surface tension of the ink in the lower part of the ink reservoir is insufficient to support a great quantity of ink and the slits provide the maximum reservoir taking the tension factor into

consideration. The widest presently contemplated width of the marking elements will produce a line approximately 28 inches in length with one filling of the ink reservoir. Narrower widths of marking elements will produce a correspondingly longer line per ink reservoir filling.

Another feature which is important to high ink capacity is the angle of inclination of the blades to their central plane. Ordinarily, pens are provided with a curved blade and opposed straight blades. However, by inclining the blades equally from their central plane, greater space between them is provided and thus the capacity of the reservoir is increased. Suitable angles of inclination are shown in connection with Figure 6.

The modification of the invention shown in Figure 7 provides a drawing pen which embodies two sets of opposed marking elements 21 and 22, each set of different width, so that two lines of different widths may be drawn with the same pen. This modification includes the feature of the cutaway portion and the slits extending upwardly, as above described, in both blades. However, instead of dividing one of the blades into a marking element and a guide element, each blade is provided with a leg which legs constitute the second set of marking elements 22. The left blade of the pen of this modification is similar in all respects to the right blade; in fact, it may be said to be a mirror image of the right blade. The edges surrounding the cutaway portion in the left blade are beveled inwardly toward the cutaway portion as and for the purpose set forth above. Each set of marking elements has its own reservoir as provided by the sides of the blade and the upwardly extending slits.

In using this modified form only one set of marking elements is supplied with ink at a time, depending upon which width line is desired. It is not desirable to fill both reservoirs at the same time because one set of marking elements must act as a guide leg and thus its reservoir would be adjacent the straight-edge. If this reservoir contains ink, such ink may flow under the straight-edge and spoil the drawing. In all other respects, this form of the pen is manipulated as is that shown in Figure 1.

Each marking element of both forms of the invention is sharpened downwardly to a thin edge so as to afford the least frictional resistance to the paper. In adjusting the ink outlet between the marking elements it is desirable to have as little space therebetween as is possible and at the same time maintain a steady flow of ink. The proper width can be arrived at by any one skilled in using drafting instruments, although it may be well to point out that as the width of the space between marking elements is increased, a greater quantity of ink flows from the reservoir and this condition may lead to an uneven line, since as the pen moves across the paper, the trailing edge of the left marking element tends to push a quantity of ink along with it, thus creating a slight build-up of ink at the end of the line. This build-up does not result when the ink outlet is wide enough only to permit steady ink flow.

It will be observed that the ink outlet space between the marking elements is rectangular and it is therefore evident that the pen will not produce an edge which is curvilinear. A mere touch of the pen to the paper will produce a straight line of length and width corresponding to that of the ink outlet and movement a short distance to the right or left will produce a square

dot or dash perfectly rectangular because such movement actually results in depositing a series of straight lines each of equal length and touching on their long sides.

In order to assure that the marking elements will at all times contact the paper properly the guide leg utilized in the first modification of this invention should terminate at its paper contacting end in the same plane as the marking elements.

While the aforesaid has related only to the production of straight lines, it is obvious that curved lines may be produced either by use of a curved edge guiding instrument such as the "French curve" or by adapting the bifurcated members to use in a compass.

I claim:

1. A drawing pen comprising, a pair of blades, each of said blades including a wide shank portion and a narrow internally and externally beveled marking portion, means for holding said blades in marking position with a V-shaped ink reservoir defined between the marking portions, one of said blades including an integral guide leg spaced from the marking portion thereof, said one blade and guide leg defining therebetween a notch wide at its mouth and extending substantially above the beginning of the wide shank portion of the other blade whereby the ink held between said beveled marking portions

15

20

25

30

cannot flow to the guide leg to foul the coaction thereof with a straight edge, said guide leg having a sharp inside edge extending substantially vertically and located centrally along the length thereof and being bent so that the midpoint of the paper contacting edge of said leg lies in the plane which passes through the central points between the marking elements.

2. A drawing pen as claimed in claim 1 where-
10 in the said guide leg is beveled toward the said notch whereby the said sharp inside edge is produced and visual anticipation of a line junc-
ture is facilitated.
